LEATHER STITCHER PRESSER FOOT
CONTROL

Eugene G. Wolf, St. Louis, Mo., assignor to Landis
Machine Company, St. Louis, Mo., a corpora-
tion of Missouri

Original application July 17, 1939, Serial No.
284,819; now Patent No. 2,273,080, dated Feb-
ruary 17, 1942. Divided and this application
October 4, 1941, Serial No. 413,583.

10 Claims. (Cl. 112—61)

The invention relates to sewing machines and particularly the type of leather stitchers used in sewing shoe soles and uppers together, and the invention consists in structure for effecting and releasing a presser foot lock and applying the presser foot to the work.

The present application is a division of an application filed by the present inventor July 17, 1939, Serial No. 284,819, now Patent No. 2,273,080, issued February 17, 1942.

It is customary in machines of this type to use a spring to thrust the presser foot towards the work at all times and to use a cam-actuated device to lock the presser foot in work-gripping position to hold the work firmly against movement over the work support during the greater part of the machine cycle but this device is released for a short period during each cycle to permit the work to be fed the length of the stitch for the succeeding operation.

The device may be connected to the presser foot by a ratchet and pawl device, the ratchet teeth being intended to accommodate variations in the thickness of the work. Obviously, the work may be of a thickness intermediate successive ratchet teeth and obviously wear on the ratchet teeth and the point of the ratchet pawl tend to make the secure locking of the work by the presser foot impermanent even though the ratchet and pawl device were effective initially for a given setting.

In another construction, the presser foot may be operated by a plurality of cam actuated devices, one of which operates the adjustment lock and the other of which operates the positive thrust on the presser foot.

The main object of the present invention is to simplify the construction for actuating a presser foot lock, as indicated, which will be secure irrespective of the thickness of the work, and which will remain secure irrespective of wear in the parts. It is further desired to construct the lock parts so they will require little space thereby facilitating assembly and replacement and also increasing the accessibility of adjacent mechanisms.

It is a further object of the invention to provide a manual release for the locking structure whereby the presser foot may be released at any time in the cycle of operations of the machine irrespective of the position of the machine cam which normally sets and releases the lock at stated periods in the cycle of operations.

These and other detailed objects of the invention as will appear from the following description

are attained by the structure illustrated in the accompanying drawings in which—

Figure 1 is a side elevation of a shoe stitcher of the type referred to, some of the parts being broken away to more clearly illustrate the mechanism. The presser foot lock is shown in functioning position.

Figure 2 is a detail section and elevation looking in the same direction and showing the presser foot released by its cam on the main shaft of the machine.

Figure 3 is a similar view showing the presser foot released by the manual control independently of the presser foot cam on the main shaft.

15 Aside from the novel presser foot control, the machine corresponds to the Goodyear type of stitchers familiar to those skilled in the art and includes a pedestal 1, a table or head 2 having brackets 3 journaling the main cam shaft 4. B indicates the work support bracket on which the shoe sole S rests. The operating ends of the usual curved awl and needle are shown at 13 and 14 respectively and oscillate about a common axis A in the usual manner.

20 25 The presser foot is formed on the forward end of an arm 16 which is moved about a fixed axis 15 and, in the normal operation of the machine, the action of the presser foot is controlled by the cam groove 10 in cam disc 9 through roller 11 on cam lever 12. The inner end 17 of arm 16 is pivotally connected to a forked jaw 18 on a rod 19 slidably mounted in a sleeve 20 which, in turn, is slidably in a member 21 having a fixed pivotal mounting pin 22 on the machine frame.

30 35 A plate 29, secured to sleeve 20, mounts a screw 30, the lower end of which engages member 21 to limit the downward movement of the sleeve through the member. A spring 32, seated on the upper end of sleeve 20, thrusts the presser foot against the work. The lower end of sleeve 20 terminates in a jaw 23. The lower end of rod 19 has a steep square thread, and a nut 24 on the threaded portion of the rod has a corrugated cylindrical exterior and is rotatable in a dog 25 seated in jaw 23, when the dog is in the position shown in Figures 2 and 3. But if the dog be tilted so that the axis of its opening is disposed angularly to the axis of rod 19, as shown in Figure 1, nut 24 is held against rotation in the dog and rod 19 is held against axial movement through the dog and the sleeve.

40 45 50 A disc 26 has an integral lateral stud 27 projecting from its far side and journalled in the lower end of the depending arm on cam lever 12 and the periphery of disc 26 is recessed or chan-

nelled to receive a roller 28. A shouldered pin 47 is mounted on the near side of disc 26 eccentrically of its axis, the small diameter portion of the pin extending across the channel in the disc and journaling the roller 28. The large diameter portion of pin 47 projects from disc 26 so that the disc may be rotated about its axis by a manually operated element 45 (Figure 3), as described below. Throughout the major portion of the cycle of operations cam groove 10 holds lever 12 in the position shown in Figure 1 and roller 28 tilts dog 25 to the position shown in Figure 1, holding nut 24 against rotation and therefore holding rod 19 against axial movement.

During a short period in the cycle of operations of the machine the restricted high portion 10a of the cam depresses cam lever 12, disc 26 and roller 28 (see Figure 2), thereby unlocking the presser foot but leaving it subject to the thrust of spring 32. Under this thrust the work may be moved across the work support bracket B by the usual feeding mechanism (not shown).

Preferably elements 10, 12, 26 and 28 are so arranged that when the parts are in the position shown in Figure 1, dog 25 will not only be tilted about the axis of rod 19 to hold the nut locked against rotation and thereby hold rod 19 against movement through sleeve 20, but the dog, rod and sleeve 20 will be moved as a unit upwardly a slight distance from the position shown in Figure 2 to thrust the presser foot into tighter engagement with the work than provided by spring 32. The extent of this movement is controlled by screw 30, the adjustment of which will vary the relation between the unit (sleeve 20, jaw 23, dog 25) and roller 28. If screw 30 is adjusted downwardly in plate 29, from the position shown in Figure 2, sleeve 20, jaw 23 and dog 25 will be raised and more of the roller upward movement will be required to tilt the dog to lock the nut before the dog, rod and sleeve are moved as a unit to positively thrust the presser foot against the work in addition to the spring thrust. Vice versa, if screw 30 is adjusted upwardly in plate 29, from the position shown in Figure 2, the sleeve, jaw and dog will be lowered relative to roller 28 and a smaller portion of the roller lift will be required to tilt the dog to lock the nut to the rod and a greater portion of the roller lift will move the dog, sleeve and rod as a unit; hence the pressure on the work will be increased.

Manually operated mechanism is provided for releasing the presser foot lock at any time in the cycle of operations of the machine. This mechanism comprises a rod 35 connected at its lower end to a foot treadle (not shown) and at its upper end to a lever 36 pivoted to a shaft 37 journalled in the machine head and connected by a link 38 to a bar 39 slidable vertically in gibbs (not shown) on the machine frame. The left hand face of bar 39 has an offset track 41 engaging the opposing face of an arm 42 pivoted at 43. A lug 44 on arm 42 (Fig. 3) engages the right hand end of a lever 45 pivoted on pin 22 and the left hand end of the lever engages pin 47 on disc 26 aligned with the journal of roller 28 but at the outer side of the disc nearest the eye.

When the treadle and rod 35 are depressed, slide 39 moves downwardly to the position shown in Figure 3 in which it thrusts arm 42 to the left, the thrust being transmitted through lever 45 to pin 47 which rotates disc 26 about its axis 27 and against the pull of spring 48 to move roller 28 to the position shown in Figure 3 in which the tail of dog 25 is freed from roller 28, which

has been holding the dog tilted, to release nut 24 and permit it to be rotated by movement therethrough of rod 19 irrespective of the position of cam groove 10, lever 12 and disc pivot 27.

5 Thereupon hook 49 on bar 39 engages pin 40 on the presser foot arm to tilt the same about its pivot 15 and lift the presser foot from the work, rod 19 moving downwardly and its threads rotating nut 24 freely in dog 25.

Spring 65 (Figure 1) returns the treadle rod and all the parts actuated thereby to normal position whenever pressure on the treadle is released.

The presser foot manual control is associated with the manual control of the thread lock 56, which is also cam actuated in the normal operation of the machine through another groove 6 in the cam disc, lever 8, and connections from the latter to the thread lock which are detailed and described in the above-mentioned earlier filed application.

25 The construction provides a positive lock for the presser foot for any given thickness of work and does not depend upon the proper spacing of a series of ratchet teeth relative to the presser foot and work-supporting bracket as is required in the ratchet type locks previously used as illustrated, for example, in Patent 1,921,277 issued to the present applicant.

30 With spring actuated or ratchet actuated presser foot locks as previously used, it has been customary to adjust the locking elements every couple weeks or so to maintain their effectiveness, whereas machines with the present locking structure have been run without adjustment for a period of six months.

35 It will be noted that a single cam actuated device locks the presser foot against movement because of the yielding of its spring 32 and also positively applies pressure in addition to the spring pressure, as may be required to grip the work firmly.

40 45 It will be understood that the presser foot lock described herein may be used independently of the thread lock although the preferred arrangement contemplates the use of both of these locks in association with each other, and their manual release by a common mechanism.

50 The principles of the invention may be embodied in structures differing in details from those illustrated and described herein and the exclusive use of such modifications as come within the scope of the claims is contemplated.

What is claimed is:

55 1. In a stitching machine, a presser foot, means for holding said presser foot against the work including a thrust-transmitting rod, a nut threaded thereon, and a tiltable dog surrounding said nut and holding it against rotation when tilted, a cam, a member actuated thereby, an element movable on said member to engage said dog so that said cam may tilt said dog to hold said nut against rotation and to shift said nut, rod and presser foot as a unit to tightly grip the work.

60 65 70 75 80 85 90 95 2. In a stitching machine, a presser foot, means for holding said presser foot against the work including a thrust-transmitting rod, a nut threaded thereon, and a tiltable dog surrounding said nut and holding it against rotation when tilted, a cam, a member actuated thereby and including a portion movable towards and away from said dog, an element movably mounted on said member to be shifted into position to oppose said dog and to tilt the same as the cam moves said

portion toward said dog, a spring thrusting said element into dog-opposing position, a part for moving said element out of said position against the thrust of said spring, and manually operable means for so moving said part and for then moving said presser foot away from the work.

3. In a stitching machine, a sleeve, a rod slideable but non-rotatable in said sleeve, a nut threaded on said rod and rotatable but non-slideable in said sleeve, a dog carried by said sleeve and associated with said nut and shiftable to position to hold the nut against rotation, a cam and a cam actuated part for shifting said dog to said position, and a presser foot arm actuated by said rod, said part, sleeve, dog, nut and rod being movable as a unit to apply positive pressure on the work through the presser foot.

4. A machine as described in claim 3 in which a spring is provided between the sleeve and the rod normally thrusting the rod to move the presser foot towards the work.

5. A machine as described in claim 1 which also includes a manually operable device having a part for moving the dog engaging element away from the dog to free the nut and having a part for shifting the presser foot away from the work.

6. A structure as described in claim 1 which includes a manually operable device movable at any time in the cycle of the cam irrespective of the position of the cam actuated member and the dog engaging element and having parts disposed to engage the presser foot and the dog engaging element to disengage the latter and to lift the presser foot from the work.

7. In a stitching machine having a drive shaft, a presser foot member, an arm carrying the same, a reciprocable rod connected thereto, a substantially stationary mounting member adjacent said rod, a jaw movably supported by said member, a nut threaded on said rod, a dog surrounding said nut and supported by said jaw and tiltable on the

latter to different positions to accommodate the rotation of the nut on the rod or to hold the nut against rotation, a cam on said shaft, and a lever actuated by said cam for tilting said dog and lifting it and said jaw, whereby the rod may be gripped and moved positively to tightly clamp the work irrespective of the thickness of the work.

8. In a presser foot mechanism for a stitching machine having a drive shaft and a work support, a reciprocating rod operatively connected to the presser foot, a sleeve slidably receiving said rod and having opposing jaw elements facing longitudinally of the axis of the rod and sleeve, a substantially stationary member slidably receiving

15 said sleeve, opposed seats on said rod and sleeve, a spring compressed between said seats and thrusting the rod and presser foot towards the work and thrusting the sleeve through said member, means on said member and sleeve limiting the movement of the sleeve under the thrust of said spring, a nut threaded on said rod and positioned between said jaw elements, a device movable to different positions to accommodate or prevent rotation of the nut on the rod, a cam on said shaft, and 20 means actuated by said cam during a portion only of the cycle of operations of the machine to move the device to lock the nut against rotation on the rod and to positively thrust the presser foot against the work.

9. A machine as described in claim 8 which also includes a member operable manually at will to engage the device moving means to release the nut from the device.

10. Structure as described in claim 8 in which the means limiting the movement of the sleeve under the thrust of the spring includes an adjustable part to vary the relative movement of the sleeve and the member receiving it and thereby controls the movement of the presser foot towards the work.

EUGENE G. WOLF.
